RACK PRIMARILY FOR HOLDING MAGAZINES IN SUSPENDED POSITION

James T. Jenkins, Apt. 303, 401 Chaplin St. SE.,
Washington, D.C. 20019

Filed Oct. 24, 1972, Ser. No. 300,310

Term of patent 14 years

Int. Cl. D6—06

U.S. Cl. D6—28

FIG. 1

FIG. 2

FIG. 1 is a front perspective view of a rack primarily for holding magazines in suspended position showing my new design; and

FIG. 2 is a top plan view.

I claim:

The ornamental design for a rack primarily for holding magazines in suspended position, as shown.
